UNITED STATES PATENT OFFICE.

PAUL W. BERG, OF TACOMA, WASHINGTON.

KNOCKDOWN CAMP BED.

Application filed March 8, 1924. Serial No. 697,360.

To all whom it may concern:

Be it known that I, PAUL W. BERG, a citizen of the United States, residing at Tacoma, in the county of Pierce, State of Washington, have invented certain new and useful Improvements in Knockdown Camp Beds, of which the following is a specification.

This invention relates to beds adapted for camp or other temporary use, and has for its objects to provide a bed which can be quickly set up or knocked down; which, when in knock-down condition, consists of only three separate parts, in which each said parts are folded so as to occupy the least amount of space, and in which said parts may all be rolled together to form a single bundle of convenient size and weight; which, when set up, can be tensioned to give a support of any desired degree of tension; which is simple and cheap to make, strong and rigid in construction, and comfortable in use.

I attain these and other objects by the devices, mechanisms, and arrangements illustrated in the accompanying drawings, in which—

Fig. 1 is a perspective view of the bed as set up for use; Fig. 2 is a side elevation 30 of a portion thereof to illustrate the tightening means; Figs. 3 and 4 are elevations of the foot and head end bars, respectively; Fig. 5 is a vertical section of the bed; Fig. 6 is a plan of one end of one of the side bars; Fig. 7 is a side elevation thereof showing the leg in the act of being folded to the side bar; Fig. 8 is a similar view showing the leg in folded position; and Fig. 9 is a similar view showing the central fold of the side bar. Similar numerals of reference refer to similar parts throughout the several views.

In camping trips of all kinds, whether of a touring nature in an automobile, or 45 hunting on foot or horseback, by canoe or boat, the arrangements for a bedstead are very important and troublesome. I have devised the following described bed which fills this need in a satisfactory manner.

Referring to the drawings: the bed consists of only three separate parts, namely the two side bars and the bed or mattress. The bed or mattress consists of a canvas or other fabric body 1, one end of which 55 is securely fastened or looped around the foot cross bar 2, and the other end of which

is attached to the head cross bar or shaft 3 in such manner that when the shaft 3 is rotated the fabric 1 is wound thereon. The foot cross bar 2 consists of a metal pipe 60 bent downward at right angles at its two ends thus forming sockets 4 into which the upper ends of the hereinafter described legs fit. The shaft 3 is rotatably mounted in two T-shaped fittings 5, at its ends, the shanks of said fittings forming sockets 6 similar to the sockets 4 above described. The shaft 3 passes entirely through said fittings 5 and one end 7 is upset to hold the fitting thereon. The other end extends 70 a short distance beyond said fitting 5 and is provided with a ratchet wheel 8 secured thereto by a pin 9.

The side bars each comprise two sections 10 and 11, secured together at the center by the pivots or hinges 12, in such manner that they may be folded together to bring their extreme ends together. Each section is made of a metal angle-iron and they are arranged to have the vertical flanges on the outside and the horizontal flanges on top (Fig. 5). The section 10 is somewhat longer than the section 11 so as to lap over said section 11, which extends only to the pivot 12. A lug 13 extends down from the end of the horizontal flange of the section 10 and enters a hole 14 in the corresponding part of the section 11 when the side bar is extended, thus holding the two sections in line when strain is applied thereto by the tension in the mattress 1 and by the load thereon. A small notch 15 is cut in the ends of the horizontal flanges of the sections 10 and 11 and is adapted to receive the legs when in operative position (Fig. 6). 95

The four legs 16 each consist of a short length of metal pipe of such size as is adapted to enter the sockets 4 and 6 above described. Each leg 16 is secured to the section 10 or 11 of the side bar, in swingable 100 manner, by means of two metal radius bars 17 and 18, each secured to the side bars and to the leg 16 by suitable pivots to permit them to turn relatively thereto. The upper radius bar 17 is relatively short and, 105 when the bed is set up, the end of the side bar horizontal flange rests directly on the said radius bar close to the leg (Fig. 7). This bar 17 is slightly offset near its connection to the said side bar in order to permit it to pass over the other bar 18 when 110 in folded position (Fig. 6). The other

radius bar 18 extends from a point on the side bar slightly further removed from the end than the corresponding end of the bar 17, to a point near the base of the leg 16. 5 The lengths of these two bars 17 and 18, and their distance apart at their two ends are such that, when the leg is swung into operative position, it is substantially at right angles to the side bar 10 or 11 to which it 10 is attached but, when it is in folded position it lies substantially parallel with and against the vertical flange of the angle iron side bar. The bars 17 and 18 are secured on the inner side of the said vertical flange 15 so that the leg 16 will come substantially opposite the middle of the horizontal flange thereof.

One of the sections 10 is provided with a short ratchet dog 19 pivoted to the outer 20 side of its vertical flange and adapted to engage the teeth of the above described ratchet wheel 8 to prevent the shaft 3 from turning to unwind the fabric 1 therefrom under the strain of the tension and of the 25 load. Since the reaction due to this ratchet dog would tend to raise the fitting 5, next to it, and draw the leg 16 out of the socket 6, I provide a pin 20 which passes through suitably registering holes in the said socket 30 6 and in the upper end of the said leg 16, whereby the said parts are securely yet removably fastened together. The pin 20 may be loosely held by a chain or wire 21 to any convenient part of the fitting 5.

35 The bed is set up by first unrolling the bundle; removing the two side bars; unfolding the bars and placing the bar having the ratchet dog next the end of the shaft 3 on which the ratchet wheel 8 is 40 mounted, and the other side bar in corresponding position on the other side; opening out the legs at one end of each bar and passing the sockets 4 over their ends; opening out the other legs and passing the sockets 6 over their ends. In this 45

position the bed is not rigid because there is no bracing against side sway or any skew bracing until the fabric 1 is tightened. This is done by inserting any suitable handle in the end of the shaft 3, engaging the pin 9 50 therein, and turning the shaft to apply tension to the fabric, which then tightens all the joints and the bed is rigid and ready for use. The fabric 1, being above the level of the side bars, tends to bend them down 55 at the center and thus prevents them from turning up on the pivots 12 when the bed is in use, and the overlapping part of the section 10 prevents their opening downward and is held firmly on top of the section 11 60 by the strain on said fabric.

Having described my invention, what I claim is:—

In a knock-down bed, the combination of two vertically foldable side bars; four legs positioned at the ends of said side bars; two radius bars of different lengths swingably attached at their ends to the side bars and to each of the legs, whereby the legs may be swung into operative position at right angles to said side bars at the ends thereof or swung back against and substantially parallel thereto; a cross bar formed with downturned sockets at its ends, said sockets removably fitting over the upper ends of two 75 of said legs; a cross shaft rotatably mounted in fittings having sockets removably fitting over the other two of said legs; removable means for securing one said fitting to said leg; a fabric secured to said cross bar and said cross shaft; a ratchet wheel mounted on the end of said cross shaft adjacent said secured fitting; and a ratchet dog mounted on the side bar adjacent said ratchet wheel and engaging the teeth thereof, whereby 85 when the shaft is rotated to wind up and tighten the fabric, the dog will hold it in tightened condition.

PAUL W. BERG.
